[57] **CLAIM**

The ornamental design for a bottle, as shown and described.

DESCRIPTION

FIG. 1 is a perspective view of the bottle showing our design;

FIG. 2 is a front elevational view thereof;

FIG. 3 is a right side elevational view thereof;

FIG. 4 is a rear elevational view thereof;

FIG. 5 is a left side elevational view thereof;

FIG. 6 is a top plan view thereof;

FIG. 7 is a bottom plan view thereof;

FIG. 8 is a fragmentary perspective view of a second embodiment of the bottle showing a cylindrical pump closure, the undisclosed broken away portion of the bottle is the same as the first embodiment;

FIG. 9 is a fragmentary side elevational view of the second embodiment, the opposite side elevational view is a mirror image thereof; and,

FIG. 10 is a fragmentary rear elevational view of the bottle of FIG. 8, the undisclosed broken away portion of the bottle is the same as the first embodiment.

FIG. 9

FIG. 10
